Primary Examiner — Kelley A Donnelly(74) *Attorney, Agent, or Firm* — Tommy SF Wang; Wang IP Law Group, P.C.(57) **CLAIM**

The ornamental design for a stackable shelf, as shown and described.

DESCRIPTION

FIG. 1 is a perspective view of a stackable shelf showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof with drawers of the stackable shelf pulled out of the stackable shelf; and, FIG. 9 is the other perspective view thereof with an additional stackable shelf drawn in broken lines.

The broken line portions of the stackable shelf in FIGS. 1-9 represent unclaimed portions of the claimed design and form no part thereof. The broken lines of the additional stackable shelf in FIG. 9 illustrate unclaimed environment and forms no part of the claimed design.
